ELECTRICAL APPLIANCE PLUG CONNECTOR

George J. Meuer, Milwaukee, Wis., assignor to
Cutler-Hammer, Inc., Milwaukee, Wis., a cor-
poration of Delaware

Application November 14, 1938, Serial No. 240,274

8 Claims. (Cl. 173—332)

This invention relates to improvements in electrical appliance plug connectors. The invention more particularly relates to improvements in electrical appliance plug connectors of the so-called "clamp type" disclosed and claimed in my Patent No. 1,898,539, dated February 21, 1933.

A primary object of the invention is to generally improve the details of construction and assembly of the parts and the operative characteristics of electrical appliance plug connectors of the aforementioned character.

Another object is to provide improved means for insuring maintenance of the parts of said device in properly assembled relation under all conditions when in use.

Another object is to provide novel means for insuring against relative lateral displacement of the casing sections, while permitting the desired degree of forcible separation of portions of the 20 adjacent faces thereof as an incident to plugging attachment of the device to a plurality of plug jacks.

Another object is to provide a novel form of resilient or flexible cord guard and novel means 25 for externally attaching the same to the casing sections.

Another object is to provide an arrangement whereby the cord guard may be utilized to restrain the external assembling and biasing clips 30 against accidental separation from the assembled parts of the casing.

Another object is to provide a device of the aforementioned character enabling use of a dowel or guide pin of simple and inexpensive form.

Another object is to provide such a device with a novel form of strain relief for the terminal ends of the wires of a conductor cord.

Another object is to provide a device of the aforementioned character having an unusually 40 neat and attractive appearance.

Other objects and advantages of the invention will hereinafter appear.

The accompanying drawings illustrate certain 45 embodiments of the invention which will now be described, it being understood that the embodiments illustrated are susceptible of modification in respect of certain details of construction there- 50 of without departing from the scope of the appended claims.

In the drawings,

Figure 1 is a front elevation (slightly larger than normal size) of a clamp type electrical appliance plug connector constructed in accordance 55 with my invention.

Fig. 2 is a side elevation of the device shown in Fig. 1.

Fig. 3 is an interior view of one of the two sections of the molded insulating casing.

Fig. 4 is a view (double scale, and partly in section) on the line 4—4 of Fig. 2, the various parts of the device being shown in assembled relation.

Fig. 5 is a vertical view on the broken line 5—5 of Fig. 1, certain parts of the device being shown 10 in elevation.

Fig. 6 is a perspective view of one of the two substantially U-shaped resilient wire clips employed in the device of Figs. 1 to 5.

Fig. 7 is a perspective view of the punched 15 insulating plate which provides a strain relief for the terminal ends of the wires, as shown in Figs. 4 and 5.

Fig. 8 is an elevation of a slightly modified plug connector as constructed in accordance with my 20 invention.

Fig. 9 is a fragmentary interior view, partly in elevation and partly in section, of the device shown in Fig. 8.

Fig. 10 is a perspective view of the alternative 25 form of punched insulating strain relief plate shown in Fig. 9, which may be substituted for the plate shown in Figs. 4, 5 and 7.

Fig. 11 is a perspective view of a still further modified form of insulating strain relief plate, 30 showing the novel manner in which the individual wires of a conductor cord may be attached thereto, and

Fig. 12 is an enlarged elevation of a fragment of the casing section shown in Fig. 4, the cylindrical dowel pin, which is adapted for a drive fit into the recess of hexagonal form in transverse cross section, being shown in elevation in separated relation.

Referring first to that form of the invention 40 shown in Figs. 1 to 7 and 12, the numerals 15 and 16 designate the pair of molded sections which jointly form the insulating casing of the connector. In practice the sections 15 and 16 are identical with each other in respect of the exterior contour and surfaces thereof, and in respect of the interior recesses thereof, with the exception that section 15 is provided with a recess 15^a (Figs. 4 and 12) of hexagonal form in transverse cross section to accommodate with a 45 drive fit either end of the cylindrical dowel pin 17 (Fig. 12), whereas the section 16 is provided with a recess 16^a (Fig. 3) of circular form in transverse cross section, and of relatively larger 50 diameter than pin 17 to freely receive the free 55

end of the latter and to permit the required degree of tilting or separating movement of sections 15 and 16, while preventing substantial lateral or longitudinal movement of said sections relatively to each other.

It follows that sections 15 and 16 may be produced (at different times) from the same set of molding dies, it being only necessary to provide a die stud or insert to produce the hexagonal recess 15^a when molding section 15, and to substitute for such die stud another stud adapted to produce the circular recess 16^a when molding section 16.

Although sections 15 and 16 might be made identical in all respects (in accordance with the teachings of my aforementioned Patent No. 1,898,589), such an arrangement requires machining of a rod or bar of hexagonal or other polygonal form in transverse cross section to provide a portion of reduced circular cross section (as shown in Fig. 7 of said Patent No. 1,898,589). With the arrangement herein disclosed, however, the dowel pin 17 (Fig. 12) is simply formed by cutting the same to the desired length from a commercially available rod or bar of circular form in transverse cross section. Other forms of doweling arrangements may, of course, be employed. Thus, if desired, the sections 15 and 16 may be provided with dowel-pin recesses of identical form and dimensions, the dowel (not shown) comprising a flat punching having a relatively large end adapted for a drive or press fit into one of the like dowel recesses and a relatively small or reduced end adapted for a relatively loose fit within the other dowel recess. The flat punched dowel in such case may, of course, be composed either of sheet metal or an insulating material of the required strength and rigidity.

Casing sections 15 and 16 (Figs. 3 to 5) are provided in the adjacent faces thereof with like complementary recesses to accommodate a pair of combined contact and terminal units 18 of identical form. Each unit 18 preferably comprises a punched and stamped sheet metal member which is bent upon itself, or reflexed, to provide at the forward end thereof a pair of contact arms arranged in socket-forming relation, the forward ends of said contact arms being flared as shown to facilitate insertion of a plug jack of suitable form (not shown) therebetween. The shank of a binding screw 19 takes into tapped openings (not shown) provided in the upper and lower layers of said terminal portion, the opening in the lower layer including an extruded rim 18^a (Fig. 5) whereby a thread of sufficient length is provided. The upper layer of each terminal portion is provided at its edges with substantially integral parallel lugs 18^b to provide a guard for a wire loop to be clamped in place by the head of screw 19.

Units 18 and the complementary recesses in sections 15, 16 are cooperatively formed to insure against substantial longitudinal or lateral displacement of the former in either direction with respect to said casing sections. Sections 15, 16 are provided at the lower ends thereof with grooves having intermediate portions 15^b, 15^c and 16^b, 16^c, respectively, with flat portions 15^d, 15^e and 16^d, 16^e at the respective opposite sides of said intermediate portions. The intermediate portions of the grooves, such as 15^b, 16^c (Fig. 5) are adapted to accommodate and guide plug jacks of substantial thickness or diameter, such as those of round or elliptical form in cross sec-

tion; whereas said intermediate portions jointly with the flat portions, such as 15^d, 16^e (Fig. 5) are adapted to accommodate thin and wide, or blade type plug jacks.

Sections 15 and 16 are respectively provided exteriorly thereof with grooves 15^f, 15^g and 16^f, 16^g extending downwardly from the upper ends thereof on opposite sides of the longitudinal center line of each casing section throughout the major portion of the length thereof. Said grooves are preferably of rectangular channel-shape in transverse cross section, and the grooves in each section are slightly curved inwardly toward each other throughout their length, as best illustrated in Fig. 1. The arrangement is such that grooves 15^f and 15^g (Fig. 5) are alined with each other, and grooves 16^f and 16^g are alined with each other. Forcibly insertable downwardly into the alined pairs of grooves 15^f, 15^g and 16^f, 16^g are a pair of flat, substantially U-shape resilient wire members 20, the wire of which said members are formed being preferably of substantially rectangular form in cross section. Members 20 when formed as shown in Fig. 6 are preferably provided with a plating of nickel.

As shown in Figs. 1 and 5, members 20 fit rather snugly within the alined grooves of the respective pairs, and in a relation substantially flush with the respective outer surfaces of the casing sections 15 and 16 (see Fig. 5). The curvature of said grooves (Fig. 1) causes a corresponding curvature or bending of the arms of members 20, to assist in restraining the latter against accidental displacement of said members from the assembled casing sections. Said curvature of the arms of members 20 also provides for application of the maximum degree of spring pressure upon the casing sections at spaced points adjacent to the longitudinal center line of the casing as a whole, and closely adjacent to the point of initial spreading of the pairs of contact arms, incidental to insertion therebetween of plug jacks. Also as shown in Fig. 6, the arms of each member 20 are initially bent or angled inwardly toward each other to insure a predetermined degree of external spring pressure upon the casing sections.

The connecting portions 20^a of members 20 are adapted to seat or rest against the upper end surfaces of casing sections 15, 16. Said casing sections are provided at the upper ends thereof with integral extensions which jointly provide a head portion 21 (Fig. 5) of substantially frusto-conical contour, with an annular groove or neck portion 22 therebelow, and an annular portion 23 (Figs. 1, 2 and 5) below said neck portion and having a diameter substantially corresponding to the maximum diameter of head portion 21. To provide clearance for wire clip members 20 and to facilitate insertion and removal of the latter, head portion 21 and annular portion 23 are provided with flats or cut-away portions 21^a (Fig. 5) and 23^a (Fig. 4), respectively.

The aforementioned extensions are provided with complementary grooves 24 and 25, which jointly provide a passage for the conductor cord 26 (Figs. 4 and 5), the outer end portions 24^a and 25^a of said grooves being relatively larger than the inner portions thereof. I prefer to provide a resilient cord guard member the lower end of which is forcibly movable downwardly over said head portion 21 and into positive but releasable engagement with the shoulder formed by said neck portion 22, the lower end of said cord guard also overlying the connecting portions of mem-

bers 20 to further assist in retaining the latter in assembled position.

In the device of Figs. 1 to 5 said cord guard is formed of a single length of resilient wire, coiled in the manner best illustrated at 27 in Fig. 1 to provide a closely wound, enlarged lower end portion 27^a of substantially frusto-conical contour to accommodate said head portion 21, the lower end coil 27^b of said guard being wound to a substantially reduced diameter, whereby the same is adapted to snap into positive but releasable engagement with the shoulder formed between neck portion 22 and head portion 21. Also as best illustrated in Figs. 1 and 4, said lower end coil 27^b is adapted to overlie the connecting portions 20^a of members 20 to assist in restraining the latter against accidental upward displacement relatively to casing sections 15 and 16. As will be apparent from Figs. 1, 4 and 5 the lower end portions 27^a, 27^b of the cord guard 27 cooperate with the casing sections to assist in restraining the latter against substantial lateral or longitudinal displacement relatively to each other. Moreover, said lower end portions of the guard 20 do not substantially interfere with the required degree of separating movement of the lower ends of the casing sections as an incident to cooperative engagement of the socket contacts with plug jacks. The upper end portion 27^c of cord guard 27 has the coils thereof spaced to a predetermined degree to afford the desired degree of flexibility thereof. Cord guard 27 is provided at its upper end with an annular sheet metal member or ferrule having a portion 28 telescoping into said cord guard, and a downwardly extending exterior flange 28^a (Figs. 1 and 2) the lower edge of which is spun inwardly, as shown at 28^b in Fig. 1 to retain said member in position, and to provide an enclosure for the cut end of the upper end coil 40 of the guard.

Casing sections 15 and 16 are respectively provided with integral upwardly and outwardly angled projections 29 and 30 of trapezoidal form, as shown in Fig. 1; portions of the exposed surfaces of said projections being grooved, as shown at 30^a in Fig. 1, or otherwise roughened to afford a proper finger grip (see Fig. 2) to facilitate attachment of the connector to or removal thereof from a electrical appliance. Casing sections 15 and 16 are likewise provided at opposite side edges thereof with complementary or matching upwardly and outwardly and then inwardly curved projections to jointly provide finger grip portions 31 and 32. The electrical appliance plug connector 55 as so constructed is very neat in appearance, and the same may be embellished by a suitable design to increase the attractiveness thereof, as shown. The ornamentation or design illustrated herein is disclosed and claimed in Design Patent No. 60 109,735, granted May 17, 1938, to C. B. Stevens.

As indicated in Fig. 5, after a slight degree of spreading of the contact arms of units 18 (upon engagement thereof with plug jacks) the arms will engage the respective blocks 15, 16 to cause 65 spreading of the latter against the spring bias afforded by the arms of the wire clips 20. The clips 20 are relatively longer and substantially heavier than the clips 22 disclosed in my prior Patent No. 1,898,589 aforementioned; whereas 70 said clips 20 insure a proper degree of pressure of the contact arms against the plug jacks under all conditions. The clips 20 and all other parts of the present device are extremely rugged and durable and are not likely to get out of order. The 75 combined contact and terminal members 18 are

formed of a suitable metal, such as brass or steel, preferably silver plated. Members 18, if formed of steel, may alternatively be provided with a plate or covering of zinc. In practice the binding screws 19 are formed of brass or steel, to correspond with the particular metal employed in forming the members 18. The screws 19, if formed of steel, may be silver plated or zinc plated; and if formed of brass the same are preferably silver plated.

In practice I prefer to provide simple means to insure against any substantial degree of strain upon the terminal ends 26^a, 26^b of the individual wires, as an incident to a pull upon the conductor cord 26, whereby to prevent accidental loosening 15 of the binding screws 19. Accordingly the casing sections 15 and 16 are internally recessed at 15^a (Fig. 4) and 16^b (Fig. 3), at the inner ends of the respective cord grooves 24 and 25, to accommodate the diametrically opposed portions of the 20 substantially circular intermediate enlargement 33^a of a flat, punched plate 33 of insulating material (see Fig. 7). Enlargement 33^a is provided with a centrally located circular opening 33^b to provide for downward insertion of conductor 26, 25 including the individually insulated wires 26^a, 26^b (Fig. 4), the outer insulating covering of the cord being cut away in a plane substantially flush with the lower surface of plate 33. Plate 33 (Fig. 7) is provided with diametrically opposed arms or 30 extensions 33^c and 33^d; arm 33^c being formed to provide grooves 33^e and 33^f, and arm 33^d being formed to provide grooves 33^g and 33^h.

In wiring the device, the insulated wire 26^a (Fig. 4), after insertion of the conductor 26 through 35 opening 33^b, is bent laterally over the lower surface of plate 33, then upwardly through groove 33^e, laterally across the upper surface of plate 33, and downwardly through groove 33^f. Wire 26^a is cut to the desired length, and a portion of 40 the free end thereof is bared and bent to hook or loop form, to provide for proper clamping engagement of the head of a screw 19 therewith. In like manner the insulated wire 26^b is bent laterally over the lower surface of plate 33, then upwardly 45 through groove 33^g, across the upper surface of plate 33, and then downwardly through groove 33^h; wire 26^b being cut to the desired length, and a portion of the free end thereof is bared and 50 bent to loop form for clamping engagement there- of by the head of the other screw 19.

Sections 15 and 16 are recessed as shown to accommodate the arms 33^c, 33^d of plate 33, the arrangement being such that the individual wires 26^a, 26^b are snubbed at a multiplicity of points 55 against plate 33, whereas a portion of each of said wires is additionally clamped between the upper surface of plate 33 and the upper end walls of the recesses formed in sections 15 and 16. As will be apparent from Fig. 4, any strain incident 60 to an outward pull upon the cord 26 is absorbed by the plate 33 and the intermediate portions of the wires 26^a, 26^b associated therewith, without reaching the bared end portions of the wires which are clamped by the heads of screws 19. I 65 have shown, and will hereinafter describe, other forms of strain relief devices which, it is to be understood, may be substituted for that illustrated in Figs. 4, 5 and 7.

The form of electrical appliance plug connector 70 illustrated in Figs. 8 and 9 is substantially like that aforescribed but differs therefrom in respect of certain structural details. Thus the insulating casing may comprise a pair of sections 34 and 35, which may be identical with each other, 75

if a doweling arrangement like that disclosed in my prior Patent No. 1,898,589 is employed; or said sections 34 and 35 may differ from each other only in respect of the relative shapes of the dowel recesses (such as 15^a in Fig. 4 and 16^a in Fig. 3), if a cylindrical dowel pin like that shown in Fig. 12 is employed. Sections 34 and 35 may be provided with complementary internal recesses exactly like those of sections 15 and 16 aforescribed.

The substantially U-shaped resilient wire clips 36 of Figs. 8 and 9 are substantially like clips 28 aforescribed, but are preferably slightly shorter than the latter. The relative shortness of clips 36 is necessitated by the fact that sections 34 and 35 are provided at the upper ends thereof with grooves 34^a, 34^b (Fig. 9) and 35^a, 35^b (Fig. 8) which accommodate, in a substantially flush relationship to the upper end surfaces of sections 34 and 35, the connecting portions 36^a of members 36. In order to facilitate removal of clips 36, as by inserting the blade of a screw driver or the like under the connecting portions 36^a thereof, the outer walls of groove 34^a, 34^b and 35^a, 35^b are angled outwardly, as shown at 34^c, 34^d (Fig. 9) and 35^c, 35^d (Fig. 8).

Casing sections 34 and 35 are respectively provided at the upper ends thereof with integral extensions, the upper ends 34^e and 35^e of which 30 jointly provide a head portion of substantially frusto-conical contour; and the lower ends 34^f and 35^f of which extensions are of reduced size, to provide an annular groove between said head portion and the upper end surfaces of sections 34 35 and 35. Said casing sections and their extensions are internally grooved, as shown in Fig. 9, which grooves jointly provide a passage for the conductor cord 26.

The cord guard in this instance preferably 40 consists of a molded resilient rubber member 37 having the external contour illustrated in full lines in Fig. 8, said member being internally recessed as shown at 37^a to accommodate said frustoconical head portion, and the same being provided with an annular inwardly extending flange 37^b which fits rather closely between said head portion and the upper end surfaces of casing sections 34 and 35. The lower end of member 37 is of sufficiently large size to overlie the grooves in 50 the upper end surfaces of sections 34 and 35 and the connecting portions 36^a of clips 36 to assist in restraining the latter against accidental upward displacement. The upper end portion 37^c of member 37 is of gradually reduced size to increase the flexibility thereof, the same being provided with a centrally located passage 37^d to accommodate with a snug fit the conductor cord 26 (see Fig. 9). Member 37 is provided at its upper end with an external annular bead 37^e (Fig. 8) 60 to strengthen the same and to provide a more finished appearance to the connector as a whole.

The strain relief device shown in Figs. 9 and 10 is in general quite similar to that aforescribed, the same comprising a flat punched insulating 35 plate 38 having an intermediate enlarged portion 38^a of substantially circular contour, with a centrally located circular opening 38^b formed therein. Member 38 is provided with diametrically opposed arms 38^c and 38^d, arm 38^c having a relatively small circular opening 38^e formed intermediate the length thereof, and a notch or groove 38^f in the outer end thereof. Similarly, arm 38^d is provided with an opening 38^g and an end groove or notch 38^h.

When wiring the connector (see Fig. 9) a por-

tion of the outer insulating covering of cord 26 is removed, and said cord is inserted through opening 38^b to the extent indicated. Wire 28^a is bent laterally over the lower surface of plate 38, with the individual insulating covering thereof removed beyond a point aligned with opening 38^b. The bared end of wire 28^a is threaded upwardly through opening 38^b, bent laterally over the upper surface of plate 38, and is then bent to extend downwardly through groove 38^c, the free end of the wire being looped as shown for clamping thereof by the head of the terminal screw 18. In like manner wire 28^b is bent laterally over the lower surface of plate 38, the bared end portion thereof being threaded upwardly through 15 opening 38^b, then bent laterally over the upper surface of plate 38, and then bent to extend downwardly through groove 38^b, the free end of the wire being looped for clamping thereof by the head of the other terminal screw 19. The 20 strain relieving function of the device upon the connections between the wire ends and the terminal screws 18 will be apparent from consideration of Fig. 9; it being noted that there are a plurality of snubbing connections between each wire 25 and plate 38, whereas an intermediate portion of each wire is tightly clamped between the upper surface of plate 38 and the complementary end walls of the recesses in sections 34 and 35, in the event of a pull upon the conductor cord 26. As 30 aforescribed, the strain relief device illustrated in Figs. 9 and 10 may be substituted for that shown in Figs. 4 and 5.

A further modified form of strain relief device adaptable for use in conjunction with either form 35 of connector is illustrated in Fig. 11, the same comprising a flat punched insulating plate 39 having an enlarged intermediate portion 39^a of substantial circular contour, said intermediate portion having a centrally located circular opening 39^b. Plate 39 is provided with a diametrically 40 opposed pair of arms 39^c and 39^d, the outer end portions 39^e and 39^f of which are enlarged as shown.

In wiring a connector plug, a predetermined 45 length of the outer insulating covering of cord 26 is removed, and the individually insulated wires 26^a and 26^b only are inserted downwardly through opening 39^b and bent laterally to underlie the respective arms 39^c and 39^d. A single length of 50 non-combustible thread of insulating material (such as asbestos) is then wound, first, in self-locking, or end snubbing, relationship around the cord 26 above plate 39, in the manner indicated at 40. Thereafter the thread is carried across a 55 portion of the upper surface of plate 39 and wound a number of times around arm 39^c and the insulated portion of wire 26^b which underlies the same, as shown at 40^a. After a few turns of the thread the same is crossed diagonally, as 60 shown at 40^b, then wound in the reverse direction a larger number of times around arm 39^c and the insulated portion of wire 26^a which underlies the same, in the manner illustrated at 40^c. The thread is then again crossed diagonally, as shown 65 at 40^d, and the winding 40^a about arm 39^d and wire 26^b completed, whereupon the remaining portion of the thread is extended across the upper surface of plate 39 and again wound a number of times around the cord 26, as aforescribed at 40. If desired, of course the thread 70 may be wound in a manner to provide for knotting or tying thereof after completion of the winding operation.

The terminal end of the asbestos thread does 75

not tend to unwind, even in the absence of a knot or other fastening means therefor, due to the fact that the projecting fibers thereof will engage and interlock with the fibers of the previously wound portions thereof. Moreover, after positioning of conductor 26 and its attached plate 39 in proper position in the recesses of the casing sections, the walls of the cord passage formed in the latter will further assist in preventing unwinding of the asbestos thread. As shown in Fig. 11, only relatively small lengths of the wires 26^a and 26^b are bared and looped for cooperation with the shanks and heads of the respective binding or terminal screws. The functioning of the device of Fig. 11 when assembled with respect to the insulating sections of the casing and other parts of the connector will be at once apparent. The upper surface of plate 39 will abut, or tend to abut, against the upper end walls of the recesses in the casing sections. In the event of a pull upon cord 26 the insulated portions of wires 26^a, 26^b are not only snubbed against the lower surface of plate 39, at the points where said wires extend upwardly through opening 39^b; but due to the relatively tight winding of the thread at 40^a and 40^b there is a very great resistance to any upward movement or slippage of the wires relatively to plate 39.

What I claim as new and desire to secure by Letters Patent is:

1. An electrical appliance plug connector comprising an internally recessed longitudinally divided molded insulating casing, the opposed sections of said casing jointly having at least one pair of aligned grooves formed therein and extending downwardly from the upper end of said casing upon the outer surface of the latter, a substantially U-shaped resilient metal clip forcibly insertable downwardly into said pair of grooves to straddle the respective casing sections to assist in retaining the latter in assembled relationship to each other, said casing sections having at the upper end thereof integral extensions with complementary internal grooves to jointly provide a cord passage, said extensions being formed externally to provide a head portion with an annular groove or neck portion therebelow, and a hollow, resilient cord guard member the lower end of which is forcibly movable downwardly over said head portion and positively but releasably engaged with the shoulder formed between the latter and said neck portion, whereby accidental upward displacement of said cord guard is prevented, said lower end of said cord guard also overlying the upper end portion of said metal clip whereby accidental upward displacement of the latter is prevented.

2. An electrical appliance plug connector comprising an internally recessed longitudinally divided molded insulating casing, the opposed sections of said casing jointly having aligned pairs of grooves formed therein and extending downwardly from the upper end of said casing upon the outer surface of the latter, a pair of substantially U-shaped resilient metal clips forcibly insertable downwardly into the respective pairs of grooves to straddle the respective casing sections to assist in retaining the latter in assembled relationship to each other, said casing sections having at the upper end thereof integral extensions with internal grooves to jointly provide a cord guide, said extensions being formed externally to provide a head portion with an annular groove or neck portion therebelow, and a hollow, resilient cord guard member the lower end of which is

forcibly movable downwardly over said head portion and positively but releasably engaged with the shoulder formed between the latter and said neck portion, whereby accidental upward displacement of said cord guard is prevented, said lower end of said cord guard also overlying the upper end portions of said metal clips whereby accidental upward displacement of the latter is prevented.

3. An electrical appliance plug connector comprising an internally recessed longitudinally divided molded insulating casing, the opposed sections of said casing jointly having two aligned pairs of grooves formed therein and extending downwardly from the upper end of said casing upon the outer surface of the latter, said pairs of aligned grooves being arranged in equally spaced relation to the longitudinal center line of said casing and extending throughout the major portion of the length of the latter, said pairs of aligned grooves being curved inwardly toward each other throughout the length thereof, a pair of substantially U-shaped flat, resilient metal clips the arms of each of which are forcibly insertable jointly into one of said pairs of aligned grooves to straddle the respective casing sections to assist in retaining the latter in assembled relationship to each other, the curvature of said grooves acting to effect corresponding curvature of the arms of said clips as an incident to insertion of the latter, to assist in restraining said clips against accidental displacement from said grooves, said casing sections having at the upper end thereof integral extensions with complementary internal grooves to jointly provide a cord passage, said extensions being formed externally to provide a substantially frusto-conical head portion with an annular groove therebelow, and an elongated, hollow, resilient cord guard member the lower end of which is formed to require forcible movement thereof downwardly over said head portion and to provide for positive but releasable engagement with the shoulder formed between said head portion and said annular groove, to thereby assist in retaining said casing sections in assembled relation and to prevent accidental upward displacement of said cord guard, said lower end of said cord guard also overlying the upper ends of said metal clips to further assist in retaining the latter in assembled relation to said casing.

4. An electrical appliance plug connector comprising a longitudinally divided molded insulating casing, said casing having a plurality of pairs of complementary recesses respectively arranged on opposite sides of the line of division thereof, a plurality of combined contact and wiring terminal units loosely positioned within the respective pairs of complementary recesses, each unit comprising a single metal member reflexed to provide a pair of contact arms arranged in socket forming relation, the opposed sections of said casing jointly having aligned pairs of grooves formed therein and extending downwardly from the upper end of said casing upon the outer surface of the latter, said pairs of aligned grooves being arranged in equally spaced relation to the longitudinal center line of said casing and extending throughout the major portion of the length of the latter, a pair of substantially U-shaped resilient wire clips the arms of which are forcibly insertable into the respective pairs of aligned grooves in said casing sections to assist in retaining the latter in assembled relation, said casing sections having at the upper ends there-

of integral extensions with internal grooves to jointly provide a cord passage, said extensions being formed externally to provide a head portion with an annular groove therebelow, a coiled 5 wire cord guard member the lower portion of which is formed to accommodate said head portion and the lower end coil of which guard is formed to snap into said annular groove, and said lower end coil overlying the upper ends of 10 said clips to restrain the latter against upward displacement.

5. An electrical appliance plug connector comprising a longitudinally divided molded insulating casing, the opposed sections of said casing 15 jointly having aligned pairs of grooves formed therein and extending downwardly from the upper end of said casing upon the outer surface of the latter, said pairs of aligned grooves being arranged in equally spaced relation to the longitudinal center line of said casing and extending throughout the major portion of the length of 20 the latter, said pairs of aligned grooves being curved inwardly toward each other throughout the length thereof, a pair of substantially U-shaped flat, resilient wire clips the arms of each 25 of which are forcibly insertable into one of said pairs of aligned grooves to straddle the respective casing sections to assist in retaining the latter in assembled relationship to each other, the 30 curvature of said grooves acting to effect corresponding curvature of the arms of said clips as an incident to insertion of the latter, to assist in restraining said clips against accidental displacement from said grooves, said casing sections 35 having at the upper ends thereof integral extensions with internal grooves to jointly provide a cord passage, said extensions being formed externally to provide a substantially frusto-conical head portion with an annular groove therebelow, 40 a coiled wire cord guard member the lower portion of which is enlarged to accommodate said head portion and the lower end coil of which guard is adapted to snap into said annular groove, whereby accidental upward displacement 45 of said guard is prevented, and said lower end coil also overlying the upper ends of said wire clips to restrain the latter against upward displacement.

6. An electrical appliance plug connector comprising a longitudinally divided molded insulating casing, said casing having a plurality of pairs 50 of complementary recesses respectively arranged on opposite sides of the line of division thereof, the opposed sections of said casing jointly having, 55 aligned pairs of grooves extending from the meeting surfaces of the casing sections and then downwardly from the upper ends of said sections upon the respective outer surfaces of the latter, said pairs of aligned grooves being arranged in 60 equally spaced relation to the longitudinal center line of said casing sections and extending throughout the major portion of the length of the latter, a pair of substantially U-shaped resilient wire clips the arms of which are forcibly 65 insertable into the respective pairs of aligned grooves in said casing sections, the connecting portions of said clips being adapted to seat within said grooves in a substantially flush relation

to the upper end surfaces of said casing sections, said casing sections having at the upper ends thereof integral extensions with internal grooves to jointly provide a cord passage, said extensions being formed externally to provide a head portion with an annular groove therebelow, and a hollow, resilient cord guard member the lower end of which is forcibly movable downwardly over said head portion and positively but releasably engageable with the shoulder formed between the latter and said annular groove, said lower end of said cord guard overlying and engaging the connecting portions of said clips whereby accidental upward displacement of the latter is prevented. 15

7. An electrical appliance plug connector comprising an internally recessed longitudinally divided molded insulating casing, a substantially U-shaped resilient metal clip straddling the respective casing sections to assist in 20 retaining the latter in assembled relationship to each other, said casing sections having at the upper end thereof integral extensions, said extensions being formed externally to jointly provide a head portion, and a hollow resilient cord 25 guard member the lower end of which is forcibly movable downwardly over and into interlocking engagement with said head portion, whereby accidental upward displacement of said cord guard is prevented, said lower end of said cord 30 guard also overlying the upper end portion of said metal clip whereby accidental upward displacement of the latter is prevented.

8. An electrical appliance plug connector comprising an internally recessed longitudinally divided molded insulating casing, the opposed sections of said casing jointly having two aligned pairs of grooves formed therein and extending downwardly from the upper end of said casing upon the outer surface of the latter, said pairs of aligned grooves being arranged in equally spaced relation to the longitudinal center line of said casing and extending throughout the major portion of the length of the latter, a pair of substantially U-shaped flat, resilient metal clips the 45 arms of each of which are forcibly insertable jointly into one of said pairs of aligned grooves to straddle the respective casing sections to assist in retaining the latter in assembled relationship to each other, said casing sections having at the 50 upper end thereof integral extensions with complementary internal grooves to jointly provide a cord passage, said extensions being formed externally to provide a head portion with an annular groove therebelow, and an elongated, hollow, resilient cord guard member the lower end of which is formed to require forcible movement thereof downwardly over said head portion and to provide for positive but releasable engagement with the shoulder formed between said head portion and said annular groove, to thereby assist in retaining said casing sections in assembled relation and to prevent accidental upward displacement of said cord guard, said lower end of said cord guard also overlying the upper ends of said 55 metal clips to assist in retaining the latter in assembled relation to said casing.

GEORGE J. MEUER.
